CLAIM

The ornamental design for a jewelry bracelet, as shown and described.

DESCRIPTION

FIG. 1 is a perspective view of the jewelry bracelet showing my new design;

FIGS. 2-5 are enlarged views thereof;

FIG. 6 is a front elevation view of the jewelry bracelet;

FIGS. 7-10 are enlarged views of the front elevation view;

FIG. 11 is a rear elevation view of the jewelry bracelet;

FIGS. 12-15 are enlarged views of the rear elevation view;

FIG. 16 is a left side elevation view of the jewelry bracelet;

FIG. 17 is a right side elevation view thereof;

FIG. 18 is a bottom plan view thereof;

FIGS. 19-22 are enlarged views of the bottom plan view;

FIG. 23 is a top plan view of the jewelry bracelet;

FIGS. 24-27 are enlarged views of the top plan view;

FIG. 28 is an additional perspective view of the jewelry bracelet; and,

FIGS. 29-32 are enlarged views of the additional perspective view.

Any broken line illustration of environmental structure in the drawings is not part of the design sought to be patented.
